UNITED STATES PATENT OFFICE.

WILLIAM McCONWAY, JR., AND ENOCH GEORGE, JR., OF PITTSBURGH, PENNSYLVANIA, ASSIGNEES TO THE McCONWAY & TORLEY COMPANY, OF PITTSBURGH, PENNSYLVANIA, A CORPORATION OF PENNSYLVANIA.

CAR COUPLER.

Application filed December 8, 1925. Serial No. 74,050.

This invention relates to car couplers and is especially suited for embodiment in devices of this character for equipping small cars such as are commonly in use around industrial plants.

The principal object of the invention is to produce a small size coupler in which the parts are exceedingly strong, durable and reliable in action.

10 A principal feature of the invention, generally stated, consists in arranging the knuckle lock upon the guard arm side of the coupler head and in forming the knuckle tail so that the portion thereof which operates with the lock projects laterally beyond the latter toward the guard arm side of the head when the knuckle is in open position.

15 A further feature of the invention consists in recessing the coupler head on its guard arm side to receive the lock and in providing the head in advance of said recess with a channel to accommodate the inner end of the knuckle tail when the knuckle is in open position, the lock and knuckle being provided with cooperating bearing faces which when the parts are in locked position are spaced from the center line of the coupler toward the guard arm side of the head.

20 Another feature of the invention consists in providing the guard arm side of the coupler head with a stop shoulder for cooperating with the inner end of the tail of the knuckle to limit outward rotation of the latter.

25 In the drawings illustrating a preferred form of the invention—

Figure 1 is a plan view of a car coupler embodying the invention.

30 Figure 2 is a side elevation of the coupler.

35 Figure 3 is a horizontal central section of the forward portion of the coupler, the rotatable knuckle being shown in plan and the parts being in locked relation.

40 Figure 4 is a detail horizontal section, the knuckle being in plan and in open position and the lock and knuckle opener mechanism being omitted.

45 Figure 5 is a view corresponding to Figure 4 but illustrating a modified construction.

The coupler body is formed with a coupler head 1 and a rearwardly extending shank 2 integrally united thereto. The knuckle 3

is pivotally mounted on the coupler head by 55 means of the usual knuckle pin 4. The lock 5 preferably employed for normally restraining an uncoupling rotation of the knuckle may advantageously be of the vertically sliding gravity actuated type. Its lifting member 6 may conveniently be of the well known type illustrated and may serve to actuate the commonly employed knuckle opener lever 7 in the usual manner. It is to be understood however that the knuckle opener may 60 be omitted if desired and that the form of lock and the character of actuating means for the latter may be varied without departing from the spirit of the invention.

On its knuckle side the coupler head is 70 recessed to form a lock receiving pocket affording an abutment wall or face 8 for supporting the lock 5 against the lateral thrusts imparted thereto by pulling strains applied to the knuckle. The abutment face 8 is 75 spaced laterally outward beyond the shank 2 of the coupler toward the guard arm side of the head 1, and the bearing face 9 of the lock which cooperates with the lock engaging face 10 of the knuckle is preferably disposed so as to be spaced from the longitudinal axis of the coupler toward the guard arm side of the head.

80 In advance of the lock 5 the coupler head is provided with an interior recess 11 which extends laterally outward beyond the lock supporting face or abutment 8. The recess 11 is preferably of channel form, terminating at its forward end in a shoulder and communicating at its rear end with the lock receiving recess of the head. The shoulder 12 forms a stop which is adapted to be engaged by the lock engaging portion 10 of the knuckle tail so as to limit uncoupling movement of the knuckle, thus preventing it from 85 passing from beneath the lock. Above and below the knuckle receiving recess 11 the coupler head 1 is preferably fashioned with oppositely extending webs or flanges 13 and 14, respectively, forming the forward inner contour of the guard arm of the coupler. The oppositely extending flanges 13 and 14 together with the intermediate channel section result in making the guard arm of the coupler head of ample strength without imparting undue weight thereto.

90 The modified form of construction shown in Fig. 5 is the same as that heretofore de-

scribed, except that outward rotation of the knuckle 3 is limited by the engagement of a stop shoulder 15 on the knuckle with a portion 16 of the coupler head which is adjacent the knuckle pin 4. Other features of construction illustrated in Fig. 5 corresponding to those shown in the principal figures of the drawings are indicated by corresponding reference numerals.

10 We claim:

1. A car coupler having reduced size standard contour and involving a coupler body having a head and shank, a knuckle pivotally mounted on said head, and a lock for the knuckle, said head being provided on its interior with a face forming an abutment for supporting the lock against the force applied thereto by the knuckle, said abutment face being spaced laterally from said shank toward the guard arm side of the head, said head being provided in advance of said abutment with a recess adapted to receive the inner end of the knuckle tail when the knuckle is in open position, and said head also being provided on its guard arm side adjacent said recess with means for preventing the knuckle tail from swinging outwardly so as to be withdrawn from beneath said lock.

2. A car coupler having reduced size standard contour and involving a coupler body formed with a head and shank, a knuckle pivotally mounted on said head, and a lock for said knuckle, said head being provided with a face forming an abutment for resisting the force applied to the lock by the knuckle, said face being substantially parallel to the longitudinal axis of the coupler and being spaced laterally beyond said shank toward the guard arm side of the coupler head,

and the inner end of the tail of said knuckle 40 having a lock engaging portion which projects laterally beyond said abutment face toward the guard arm side of the coupler head when the knuckle is in open position.

3. A car coupler having reduced size standard contour and involving a coupler body having a head and shank, a knuckle pivotally mounted thereon, and a lock for the knuckle, said head being provided on its interior with a face forming an abutment 50 for supporting the lock against force applied thereto by the knuckle, said face being spaced laterally from said shank toward the guard arm side of the head, said head having a recess on its guard arm side 55 for accommodating the inner end of the tail of the knuckle when the latter is in open position, and also being provided on its guard arm side with a stop for limiting outward rotation of the knuckle to prevent the latter from passing wholly from beneath said knuckle.

4. A car coupler having reduced size standard contour and involving a coupler head, a knuckle pivotally mounted thereon, and a lock for the knuckle, said head being provided on its guard arm side with a recess for receiving the lock and also being formed on the guard arm side with a channel in advance of said recess and communicating with the 70 latter, said channel being closed at its forward end and adapted to accommodate the inner end of the knuckle tail when the knuckle is in open position.

In testimony whereof we affix our signatures.

WILLIAM McCONWAY, JR.
ENOCH GEORGE, JR.
